UNITED STATES PATENT OFFICE.

JAMES H. QUINBY, OF SAN JOSE, CALIFORNIA.

METHOD OF FORMING FLANGE-GROOVES AND MOLDS THEREFOR.

1,255,050.

Specification of Letters Patent. Patented Jan. 29, 1918.

Application filed June 12, 1917. Serial No. 174,245.

To all whom it may concern:

Be it known that I, JAMES H. QUINBY, a citizen of the United States, and resident of San Jose, in the county of Santa Clara and State of California, have invented a certain new and useful Improvement in the Methods of Forming Flange-Grooves and Molds Therefor, of which the following is a specification.

10 My invention relates to a method of forming a groove in asphalt paving along the inner side of the ordinary T rail where the flange of the car wheel operates, and to providing a suitable strip for the molding of said groove.

It is, of course, obvious that in paving that portion of a road or street lying between car rails a space must be provided close to the inner edge of each rail to accommodate the flanges on the car wheels. When an asphalt paving is used this space or groove is sometimes provided by using a "Trilby" rail so that no groove is required in the pavement itself, but this is necessarily 25 such an expensive method of providing the required groove that a T rail is ordinarily used and the groove worked in the pavement by hand labor while the said paving is being laid.

30 The formation of this groove by hand labor is objectionable for several reasons. It is far from being uniform, and pockets are formed in which dirt and refuse accumulate. The slope of the side of the groove 35 is so gradual that it offers a noticeable depression to vehicle wheels when crossing the rails at right angles, and permits vehicle wheels to drop into the groove when running parallel with the track with the resulting serious difficulty and danger of turning 40 the same back to the normal surface of the road. In the finished asphalt pavement the voids must be reduced to a minimum, therefore hand worked grooves cannot be as permanent as the roller finished main surface as the required compression is effected 45 only to a slight depth while in the roller finished surface the required compression is effected throughout the entire depth of the asphalt. The natural result is that the shoulder of the groove is easily worn and broken away and requires constant repairing.

It is, therefore, the object of my invention 55 to provide a method providing substantially all of the advantages of the "Trilby" rail,

overcoming all of the difficulties enumerated above, and effecting a substantial saving in material and labor.

In the accompanying drawing, which will 60 illustrate the practical application of the method,

Figure 1 is a sectional, perspective view through a rail and a portion of street paving with mold in position after rolling. 65

Fig. 2 is a transverse cross section through a rail and a portion of street paving after the same has been rolled and the mold removed.

Similar characters of reference refer to 70 similar parts throughout the several views.

At 1 is indicated a T rail, at 2 is indicated a portion of the concrete base of the street or road pavement, and at 3 is indicated the finished asphalt surface of that 75 portion of the pavement on the outer side of the rail 1. At 4 is indicated a strip of suitable material, preferably wood, having, in the present instance, a top surface 5 about three inches wide, a surface 6 at right angles 80 to surface 5 and about one and five-eighths inches wide, and a third, or compression, surface 7 substantially flat throughout about one and one-half inches of the lower portion of its width and then curving upwardly 85 and inwardly in the form of an ogee curve to join the inner edge of surface 5.

When the asphalt 8 is placed in position on the inner side of rail 1 and on concrete base 2 and is prepared for rolling, strip 6 is 90 placed in the position shown in dotted lines at 6^a in Fig. 2, dotted line 8^a indicating the surface of the asphalt before rolling. When the said asphalt is rolled the strip is likewise rolled and forced into the position 95 shown in Fig. 1, thereby compressing the underlying asphalt to substantially the same degree as the balance of the asphalt and forming a hard and permanent groove in which the flange 9 of car wheel 10 may 100 freely operate. I have found that by forming compression surface 7 as shown and above described I can form a groove with a permanent, hard, compressed surface which presents no edges that will break away, that 105 is uniform in size and wearing qualities, that requires no hand tooling, and that in no way interferes with the passage of vehicle wheels in any direction, and that satisfactorily withstands the wear and scraping 110 of wheels traveling parallel with and close to the inner edge of the rail.

In Fig. 2 the dotted line 6^b indicates that mold 4 may be first positioned in a substantially horizontal position, but the position shown at 6^a is deemed the best because the mold having its outer edge positioned against the rail as at 11 the rolling of the same causes it to exert an inward as well as a downward pressure at point 12 where the greatest strength and therefore the greatest compression is required. It has been found that in forming the shoulder of the groove as above set forth the results are substantially equal to those secured by the use of the "Trilby" rail and at very considerable reduced cost.

I claim:

1. The method of forming a flange groove in asphalt pavements along the inner side of a rail, which consists in positioning a mold strip parallel with the inner edge of the rail and upon the asphalt prepared for rolling, rolling the strip simultaneously with the asphalt, and finally removing the said strip.
2. The method of forming a flange groove in asphalt pavements and along the inner side of a rail, which consists in bedding a mold strip in the asphalt parallel with the rail and against its inner edge and with the inner edge of its upper surface substantially

flush with said asphalt, said asphalt being in condition for rolling, then rolling the said strip simultaneously with the said asphalt and finally removing the said strip.

3. The method of forming a flange groove in asphalt pavements and along the inner side of a rail, which consists in bedding a mold strip in the asphalt with its upper and outer edge substantially parallel with and a distance above the upper and inner edge of the rail, and its upper and inner edge substantially flush with said asphalt, said asphalt being in condition for rolling, then rolling the said strip simultaneously with the said asphalt and finally removing the said strip.

4. The method of forming a flange groove in asphalt pavements and along the inner side of a rail, which consists in bedding a mold strip having an ogee compression surface in the asphalt and parallel with the inner edge of the rail, said asphalt being prepared for rolling, then simultaneously rolling said asphalt and said strip, and finally removing said strip.

In testimony whereof I have hereunto affixed my signature this 7th day of June, 1917.

JAMES H. QUINBY.
